C. H. TOFFELMEYER

BUILDING TILE

Filed Sept. 25, 1922

UNITED STATES PATENT OFFICE.

CHARLES HENRY TOFFELMEYER, OF HAMILTON, ONTARIO, CANADA, ASSIGNOR OF
ONE-HALF TO SIDNEY SMITH CURTIS, OF HAMILTON, CANADA.

BUILDING TILE.

Application filed September 25, 1922. Serial No. 590,420.

To all whom it may concern:

Be it known that I, CHARLES H. TOFFELMEYER, a subject of the King of Great Britain, and a resident of the city of Hamilton, in the county of Wentworth, in the Province of Ontario, Dominion of Canada, have invented certain new and useful Improvements in Building Tiles, of which the following is the specification.

10 My invention relates to improvements in building tiles with particular reference to what are commonly known as interlocking wall-tiles and the object of the invention is to devise a tile of this type which when laid will of itself present a fully finished exposed wall surface thus eliminating the necessity of surfacing the tile wall with stucco, brick or other material, after the tile wall is erected; a further object is to make 15 the tile of such shape that the process of laying will be simplified and shortened thus effecting a reduction in labor costs, and a still further object is to do away with the use of filler pieces of various shapes required when building with former interlocking tiles thus further reducing building 20 costs.

My invention consists essentially of a main tile of L-shape, the end face of one 30 leg of which constitutes a finished exposed wall surface, and a filler tile adapted to lie within the recess formed in the main tile by the diverging legs thereof, one edge of said 35 filler tile constituting a finished exposed wall surface of similar size and shape to the aforesaid exposed face of the main tile, all as hereinafter more particularly described and illustrated in the accompanying drawings in which:

40 Fig. 1 is a vertical cross section through a portion of a wall showing the application of my improved tile.

Fig. 2 is a perspective view of a portion of a wall in which my tiles have been used.

45 In the drawings like characters of reference indicate corresponding parts in the different views.

1 indicates a foundation supporting a wall 2 composed of L-shaped main tiles 3 and filler tiles 4.

5 and 6 are the two diverging legs of the L-shaped tile 3, and 7 is the recess formed in the tile by these legs 5 and 6.

The tiles are cored at 8 and the longer

faces 9 and 10 are grooved at 11, after the usual well known manner.

12 is mortar.

13 is an end face of the leg 6, and 14 is the outer exposed edge face of the filler tile 4.

The thickness of the leg 6, indicated by the letter "A", is equal to the thickness of the filler 4, indicated by the letter "B" and each of these dimensions is just slightly less than one half the total thickness of the tile indicated by the letter "C". The amount by which the sum of the thickness "A" and "B" is less than "C" is equal to the thickness of the layer of mortar "D". This will be referred to hereinafter.

70 The construction and manner of using my improved building tiles is as follows.

The main tile 3 is laid so that the edge 10 is horizontal with the edge 9 facing backwardly away from the front face of the wall. The face 13 of the leg 6 forms a part of the outer exposed face of the wall.

The tiles 3 and 4 are of the same length and the filler tiles 4 are laid above the branches 6 and within the recesses 7, the wall-tiles being staggered after the usual manner of laying bricks (see Fig. 2).

Owing to the shape and size of the tiles it is to be noted that the filler tiles 4, with the layer of mortar 12, exactly fill the recesses 7 as regards height and therefore the laying of these fillers completes the tile unit into rectangular shape and provides a proper level surface upon which to lay the next tier of tiles.

90 Further, the exposed faces 13 and 14 of the main tile 3 and filler tile 4, constitute the entire exposed surface of the wall and, since they are of similar dimensions, a proper uniform exposed wall surface is presented (see Fig. 2).

These exposed faces 13 and 14 are preferably surface finished to represent a standard building brick in size and surface finish, and therefore, when the laying of the tiles is completed, the exterior surface finish of the wall is also completed and the wall presents the appearance of an ordinary brick wall.

Formerly the types of interlocking tiles used did not permit of the accomplishment of the above result and it was necessary to surface finish the wall after laying the tiles, by stucco, brick veneer or other suitable

means. This of course involved great extra expense both of material and time.

It is to be noted that with my improved tile one shape of filler tile only is used.

5 Hitherto with the various shapes of tiles used such as the T-shape it has been necessary to use a number of different shaped fillers and of different sizes, since the interstices between the tiles were of irregular 10 size and shape.

This involved considerable additional material cost and the process of laying was much slower.

As before mentioned with my tiles the 15 completion of each tier presents a flat regular top surface.

This is an important feature since it facilitates the placing of scantling, frames, sills and such like without the necessity of breaking 20 the tiles as would be the case were a flat surface not so conveniently available.

While I have referred to the application of my invention to tiles in which a wall giving the appearance of an ordinary brick wall is obtained, this could of course be altered as desired by changing the size and 25 surface finish of the tile.

From the foregoing it will be evident that I have devised a building tile which should prove of great value to builders.

30 What I claim as my invention is:

A wall structure comprising main tiles and a filler tile associated with each main tile, each filler tile situated within a recess in a main tile, the tiles being so formed that 35 the cross section of each pair of assembled main and filler tiles is rectangular.

CHARLES HENRY TOFFELMEYER.
